INTERNAL COMBUSTION LOCOMOTIVE

Application filed October 17, 1927. Serial No. 226,666.

Diesel locomotives with compressed air transmission are known, in which the Diesel engine drives a separate compressor which supplies the compressed air required for performing work in the locomotive cylinders. The construction in question is quite suitable for small and medium locomotives, but in the case of high power locomotives has the drawback that the whole installation becomes comparatively heavy and expensive. Moreover, these locomotives necessitate the use of recooling installations for the cooling water of the Diesel engines and the compressor, which installations increase with the increase in the size of the locomotive, and in that way the difficulties of construction are still further increased and in the case of very large engines, make it even necessary to tow a separate cooling car.

The method of working according to the present invention has the advantages of the compressed air transmission, whilst avoiding the drawbacks above referred to by again compressing in the locomotive cylinders, to the temperature of ignition of the fuel, the compressed air supplied by the compressor after it has done its work in the locomotive cylinders, and by then injecting fuel into the said compressed air. The Diesel engine has therefore to supply only a small portion of the locomotive power, which is then increased in the locomotive cylinders owing to the latter operating during the second part of a working cycle as an internal combustion engine, after having worked during the first part of the cycle as an air motor.

Before its admission into the locomotive cylinders, the compressed air is preferably preheated to such an extent that, after work has been performed, a compression to the pressures hitherto usual in locomotives (about 15 atmospheres) is sufficient for the automatic ignition of the fuel. For heating the compressed air the exhaust gases of the internal combustion engine are preferably used, though naturally any other suitable means could be used for the purpose.

Reference is herein made to the copending application of Josef Geiger, Serial No. 94,516, filed March 13, 1926, for internal com-

bustion locomotives, which discloses subject matter embodied herein.

In the drawings, in which is disclosed a preferred embodiment of the invention

Fig. 1 illustrates an indicator diagram for the method of working in accordance with this invention;

Fig. 2 is a diagrammatic elevational view with parts in section of a locomotive constructed in accordance with this invention;

Fig. 3 discloses in the nine views marked Positions 1 to 9 respectively the positions of the piston, controlling valve and related parts of the driving cylinder of the locomotive during a complete cycle of operation.

Compressed air at comparatively low pressure which is generated in a separate compressor *b* driven by the Diesel engine *a* (Figure 2), after having been preheated to a suitably high temperature, is admitted into the locomotive cylinder or cylinders as indicated by the line 1—2 of the indicator diagram of Figure 1. The heating of the compressed air could be effected for instance by means of the exhaust gases from the Diesel engine in a heater *c* heated by the same. Let it be assumed that the compressed air thus preheated before admission into the locomotive cylinder *d* has for instance a pressure of 8 atmospheres and a temperature of 350° C. From the points 2 to 3 of Figure 1 expansion of the compressed air takes place. Shortly before the dead center position of the piston at 3 the controlled outlet valve *e* will be opened and during the reversal of stroke will allow the compressed air to expand to such an extent that the pressure will be equalized with that of the surrounding atmosphere. At 4 the outlet valve will be closed, and the air still contained in the locomotive cylinder will then be compressed to about 15 atmospheres during the return of the piston, its temperature, owing to the preheating, rising to such an extent that the fuel injected will be automatically ignited (point 5 of Figure 1). Into this highly heated air is injected through the nozzle *f* fuel which thereupon burns for instance at a constant pressure (in Figure 1 from 5 to 6). From 6 to 7 expansion of the

100

burnt gases then takes place. The locomotive cylinder works during this stroke as an internal combustion engine. At 7, shortly before the end of the stroke, the outlet valve is opened and then, up to the point 8 of Figure 1, the exhaust stroke follows. The end of the expansion of the compressed air at the point 4, and the end of the expulsion of the burnt gases at the point 8 are controlled by one and the same control element, viz: the cam disc g having the two cams g^1 and g^2 which are designed accordingly. Beginning at 8, a short compression of the burnt gases still contained in the cylinder takes place, and at the point 1 then begins the renewed admission of compressed air. The working cycle is thereupon repeated in the manner above described.

Referring to Fig. 3, the positions of the piston d' , controlling valve e and cam disc g are illustrated for the cycle of operation above described. Pos. 1 of Fig. 3 illustrates the parts at the beginning of the air motor stroke of the piston d' . The valve e which is actuated through the cam disc g on a cam shaft driven from the driving shaft of the locomotive at half the shaft speed in any well-known manner, is moving toward the right as shown in this view. The valve e at this time is in such position that the intake passage h' formed within the wall of the driving cylinder is in communication with the pipe h which supplies compressed air from the pre-heater c to the driving cylinder, the compressed air acting upon the piston d' to perform a working stroke. The introduction of compressed air is indicated in the diagram of Fig. 1 by the line 1—2.

In Pos. 2 of Fig. 3, the valve e has been moved to close the intake passage h' , and the air then within the cylinder expands as indicated by the line 2—3 of the indicator diagram. In Pos. 3 of Fig. 3, the valve e has been moved to the right a sufficient distance to open communication between the passage h' and an exhaust passage i' also formed within the wall of the driving cylinder, so that the air within the cylinder may exhaust to substantially atmospheric pressure as indicated by the line 3—4 of Fig. 1. At the completion of this exhausting, the valve e and the piston d' have assumed the positions shown in Pos. 4 of Fig. 3, the passage h' being again closed by the valve e . On the return stroke of the piston, the air remaining within the cylinder is then compressed to about 15 atmospheres, as indicated by the line 4—5 of the indicator diagram. Due to this compression, the air is heated to a point sufficient to cause self-ignition of fuel injected therein.

The beginning of fuel injection takes place at the point 5, with the parts as shown in Pos. 5 of Fig. 3, this fuel injection taking place over the line 5—6 of Fig. 1. The parts

at substantially the end of fuel injection are indicated in Pos. 6 of Fig. 3, spontaneous combustion of the fuel with the recompressed air taking place during the period of injection. The expansion of the combustion gases then takes place as illustrated by the line 6—7 of Fig. 1. At the point 7 the valve e again opens communication between the passage h' and the exhaust passage i' , as indicated in Pos. 7 of Fig. 3, to permit the escape of the exhaust gases. The exhaust gases are expanded from the cylinder up to the point 8 of Fig. 1, when as illustrated in Pos. 8 of Fig. 3 the valve e again closes communication between the passage h' and the passage i' . A short compression of the gases then remaining in the cylinder takes place as indicated by the line 8—9, and at point 9 with the parts as shown in Pos. 9 of Fig. 3, the valve e again connects the passage h' with the compressed air pipe h . The cycle then repeats itself in the manner above described.

Any conventional type of fuel pump and driving connection therefor can be used for supplying fuel in controlled manner to the nozzle f ; also any conventional driving interconnection from the locomotive driving axle to the cam shaft containing the cam disk g can be used. As shown, a gear l is pinned to the shaft k on which is fastened the cam g . The gear l is interconnected by a driving chain m with a pinion n pinned to the axle o of the locomotive. The shaft k is thus driven by the driving axle o of the locomotive and the ratio of the gears n and l is such as to provide a driving ratio of one to two between the axle o and the shaft k . Also pinned to the shaft k is a cam plate p , shown in dotted lines, this cam plate serving to drive the fuel pump r by acting upon the pump plunger r' , the plunger r' carrying a roller riding upon the surface of the cam plate p in the customary manner. The fuel pump is of the standard cam driven type and is connected with the injection nozzle f by injection piping s . The cam plate p is mounted upon the shaft k at such an angle relative to the cam plate g that the injection of fuel at the nozzle f takes place in controlled time relation with respect to the operation of the driving cylinder d , this fuel injection corresponding to Pos. 5 of Fig. 3. Thus during operation of the driving cylinder d with corresponding movement of the driving axle o of the locomotive, the cam plate p on the shaft k is driven by means of the interconnection m from the axle o so as to operate the fuel pump. On the down stroke of the plunger r' , fuel is drawn in past the suction valve of the pump, and on the up stroke of the plunger r' , this fuel is forced through injection pipe s and through the nozzle f into the combustion space of the driving cylinder d . At the same time, the valve e is driven in coordinated time relation by means

of the cam plate *g*, also mounted on the driven cam shaft *k*.

It is thus seen that the driving cylinder of the locomotive functions as a four-cycle Diesel engine, to which compressed air from the compressor *b* is supplied during the suction stroke of the engine operation. The result is that two-cycle operation is in fact secured, as each driving stroke of the piston is a working stroke. The engine functions on one stroke as an air motor, and on the alternate stroke as an internal combustion engine. Thus the driving cylinder of the locomotive functions as a combined air motor and internal combustion engine. The operation of the driving cylinder is controlled by the single control valve *e* which is driven by a cam shaft in the usual manner so that the operation is coordinated with that of the power cylinder, this control valve *e* regulating the admission of compressed air to the cylinder for the air motor working stroke therein, the exhaust of expanded air from the driving cylinder after the air motor stroke therein, and the exhaust of products of combustion from the driving cylinder after the internal combustion engine working stroke therein. The Diesel engine *a*, driving the compressor *b*, need only furnish a part of the power necessary in the operation of the locomotive, the balance being furnished by the internal combustion engine operation within the locomotive driving cylinder. This invention enables the Diesel engine and compressor driven thereby to be built in smaller sizes, and the building of such locomotives is considerably simplified.

While the form of apparatus herein described constitutes a preferred embodiment of the invention, it is to be understood that the invention is not limited to this precise form of apparatus, and that changes may be made therein without departing from the scope of the invention which is defined in the appended claims.

What is claimed is:

1. A combined air motor and internal combustion engine of the character described, comprising a cylinder, a piston therein, said cylinder having an intake passage and an exhaust passage, means for supplying compressed air to said intake passage for air motor operation therein on each alternate working stroke, means for supplying fuel to said cylinder for internal combustion engine operation therein on each alternate working stroke intermediate air motor working strokes, and a single control valve for governing the admission of compressed air to said cylinder for the air motor operation, the exhausting of expanded air from the driving cylinder resulting from said air motor operation, and the exhausting of products of combustion from the driving cylinder.

resulting from said internal combustion engine operation.

2. In a locomotive constructed for cooperatively combined air motor and Diesel engine operation in a working cylinder, the method which comprises preheating compressed air, introducing the preheated compressed air into the cylinder for air motor expansion therein to effect work, coordinating the preheating of the air and the expansion thereof in the air motor operation with the compression pressure to be attained during the Diesel operation so that expanded air from the air motor operation has a residual temperature above normal atmospheric temperatures, controlling the exhaust cut off of the air motor operation so as to leave a predetermined amount of expanded air having such residual temperature within said cylinder with resultant recompression thereof to the said compression pressure to attain an ignition compression temperature in excess of the compression temperature normally resulting from such a compression pressure, and injecting fuel into such recompressed air with resulting self-ignition and combustion to produce a Diesel operation and effect work, the self-ignition being thereby attained in the Diesel operation without the employment of unduly high compression pressures.

3. An engine of the character described comprising a combined air motor and Diesel engine cylinder, means for supplying heated compressed air to said cylinder with resultant expansion therein to perform a working stroke of air motor operation, means for controlling the exhaust of said expanded air so as to retain a portion thereof within said cylinder after expansion in the air motor operation, said retained air being at a temperature in excess of normal atmospheric temperatures whereby upon recompression of said remaining air to a predetermined compression pressure of the order of fifteen atmospheres, a compression temperature is attained sufficiently high to induce self-ignition of fuel injected thereinto, and means for introducing fuel into said compressed air with resultant self-ignition and combustion to produce Diesel operation on another working stroke.

4. In a locomotive of the character described having a driving axle, a combined air motor and Diesel engine driving cylinder for said locomotive, a piston therein operatively connected to said driving axle, means for supplying highly heated compressed air to said driving cylinder with resultant expansion for air motor operation therein to drive said piston on one working stroke, means driven in coordinated time relation with said piston for controlling the exhaust of said expanded air to retain a portion of said air within said cylinder sufficient to provide combustion air for a working stroke of

- Diesel engine operation, the temperature of the heated compressed air, its expansion, and exhausting in air motor operation being co-ordinated with the compression pressure to be attained in the Diesel operation such that
- 5 upon recompression of said retained air to a compression pressure of the order of fifteen atmospheres, a temperature is attained sufficiently high to provide for self-ignition of fuel injected thereinto, and means for injecting fuel into said recompressed air with resultant self-ignition and combustion for Diesel operation therein to drive said piston on an alternate working stroke.
- 10 5. In a locomotive constructed for cooperatively combined air motor and Diesel engine operation in a working cylinder, the method which comprises introducing pre-heated compressed air into the cylinder for air motor expansion therein to effect work, controlling the exhaust cutoff of the air motor operation so as to leave a predetermined amount of expanded air having a residual temperature above normal atmospheric temperature within said cylinder, recompressing such retained expanded air within the cylinder to a compression pressure of the order of 15 atmospheres, and injecting fuel into such recompressed air with resultant self-ignition and combustion to produce a Diesel
- 20 operation and effect work.
- 25 30

In testimony whereof I hereto affix my signature.
